ALKYLATION OF NAPHTHENES

Aristid V. Grosse, Chicago, Ill., assignor to Universal Oil Products Company, Chicago, Ill., a corporation of Delaware

No Drawing. Application August 9, 1937.
Serial No. 158,202

4 Claims. (Cl. 260—666)

This invention is more particularly related to reactions which occur between a relatively stable group of hydrocarbons comprising the naphthenes having 6 carbon atoms in the ring and the members of a relatively unstable group comprising cycloparaffins having less than 5 carbon atoms in the ring.

More specifically the invention is concerned with catalytic processes which enable the production of higher molecular weight derivatives of the more stable 6 carbon atom naphthenes by the addition of alkyl groups through the agency of the designated cycloparaffins.

The art of synthesizing organic compounds and particularly those of a hydrocarbon character with which the present invention is concerned is important in view of the fact that special hydrocarbons in any one series may have peculiar characteristics rendering them suitable for use either as a basis for the development of useful derivatives or direct use in hydrocarbon mixtures such as, for example, those employed as fuels for internal combustion engines, lubricants, etc., and the present invention is a contribution to the art of catalytically synthesizing such hydrocarbons.

In one specific embodiment the invention comprises treatment of relatively stable and ordinarily unreactive naphthenes having 6 carbon atoms in the ring with cycloparaffins containing 3 and 4 carbon atoms in the ring and comprising cyclopropane and cyclobutane to form alkylated derivatives of the 6 carbon atom naphthenes while utilizing metal halide catalysts and particularly aluminum chloride, under relatively low temperature conditions.

The term naphthenes is herein used to designate polymethylene ring compounds having 6 or more carbon atoms in the ring and which may or may not be substituted at various points by alkyl radicals. The simplest compound of this group is the compound designated as hexamethylene or cyclohexane. Naphthene hydrocarbons occur in practically all petroleums though in varying proportions depending upon the source of the crude oil and it is one of the features of the present invention that the naphthenic hydrocarbons present in petroleum distillates may be alkylated by cyclopropane and/or cyclobutane to form higher molecular weight derivatives.

The cyclopropane and cyclobutane necessary for the process may be produced by the action of sodium on dihalogen derivatives of propane and n-butane respectively in which halogen substitution is on the end carbon atoms. The reactions of this method of formation are shown in the following equations.

Other methods of manufacture may be employed involving various types of condensation and cyclization reactions although the above is generally the simplest and most practical. The principal properties of the two cycloparaffins are given below:

Compound	Boiling point, °C.	Specific gravity at 4° C.
Cyclopropane	-35	0.7038
Cyclobutane	11-12	

Since the two cycloparaffinic compounds shown above are gaseous at ordinary temperatures, the methods of operation whereby they are used to alkylate the ordinary 6 carbon atom naphthenes are relatively simple and consist generally in passing cyclopropane or cyclobutane or a mixture of the two into the liquid naphthene hydrocarbons containing suspended therein finely divided anhydrous aluminum chloride or other catalytically reactive metal halides such as, for example, zirconium chloride. The effective action of such catalysts requires the concurrent use of a small proportion of a hydrogen halide such as hydrogen chloride, and this compound is preferably admitted to the reaction zone in admixture with the cyclopropane or cyclobutane. Operations may be conducted according to the batch system in which the mixture of cycloparaffin and hydrogen halide is passed into a static body of naphthenic hydrocarbon liquid.

until the desired degree of alkylation is effected or continuous systems may be employed in which the cycloparaffin and hydrogen halide are injected into a moving stream of liquid hydrocarbons containing suspended halide catalyst. After an alkylation operation the solid catalytic material is allowed to settle and the supernatant liquid decanted and subjected to fractional distillation for the recovery of individual compounds or selected fractions. The alkylated products may be washed with caustic soda or other alkalies to remove traces of halogen acids or acid products of the reactions and the spent catalyst may be treated by any necessary method to restore it to the condition fitting it for further service.

The present process is applicable to the treatment of either straight run or cracked gasolines with 3 and 4 carbon atom cycloparaffins since all such gasolines contain varying percentages of naphthenes as well as paraffins and aromatics, the cracked gasolines containing in addition definite percentages of olefins. In the treatment of gasolines with the reactive cycloparaffins the principal reactions involve the addition of the propyl and the butyl radicals to the various hydrocarbon components, the mechanism involving the opening of the 3 and 4 carbon atom cycloparaffin rings to furnish the propyl and butyl groups.

The temperatures of operation are preferably maintained at points below normal atmospheric temperature when using aluminum chloride and hydrogen chloride which is in general the preferred catalyst combination both on account of the availability and relative cheapness of these materials and their effective action when used in proper proportions. Thus temperatures of approximately -40 to +10° C. are utilizable in the case of individual naphthalene hydrocarbons or naphthalene hydrocarbon mixtures which are liquid under these conditions. In the case of higher molecular weight compounds which may be normally solid, these may be treated at more elevated temperatures and in the presence of less active catalysts than aluminum chloride, such as, for example, the zirconium chloride already mentioned which usually functions better under these conditions.

The following example is given to indicate the types of reactions involved in the process of the present invention although the numerical data is not presented with the intent of unduly limiting its scope.

Methyl cyclohexane was maintained at a temperature of approximately -10° C. and about 10% of its weight of finely divided anhydrous aluminum chloride was maintained in suspension by mechanical stirring. To effect the manufacture of propyl derivatives, a mixture of dry hydrogen chloride and cyclopropane was introduced into the liquid at a slow rate corresponding to complete absorption of the cyclopropane until approximately the molecular equivalent had been introduced at which time the run was stopped and the liquid product washed and neutralized and subjected to analysis to determine its character. The principal reaction involved is shown in the appended equation since the product was

substantially all methyl propyl cyclohexane as shown on the right-hand side of the equation.

The methyl propyl cyclohexane was obtained as a water-white, narrow boiling fraction, boiling from 166.5° to 168.5° C. at 745 mm., having an index of refraction.

15

$n_{D}^{20} = 1.4333$ at 25.7°
density, $d_{4}^{20} = 0.7897$

mol. wt. 135; C=85.24% and H=14.47%. The presence of the cyclohexane ring in this product was proved by dehydrogenating at 250° C. with a platinum-on-alumina catalyst and converting it to an extent of about 95% into aromatic hydrocarbons. No compounds boiling between methyl cyclohexane and methyl propyl cyclohexane were obtained, and also no gaseous products or unreacted cyclopropane. However, some high boiling material, probably consisting of methyl dipropyl cyclohexane, was also formed. The yield of mono propyl derivatives was approximately 40% by weight of the original methyl cyclohexane while there was a 20% production of dipropyl compounds.

The nature of the present process and the character of the results obtainable by its application are evident from the preceding specification and single numerical example although neither section is intended to unduly limit its scope.

I claim as my invention:

1. A process for the production of alkyl derivatives of naphthalene hydrocarbons having at least six carbon atoms in the ring which comprises reacting the naphthalene hydrocarbon with a cycloparaffin having less than 5 carbon atoms in the ring in the presence of a metal halide and a hydrogen halide.

2. A process for the production of alkyl derivatives of naphthalene hydrocarbons having at least six carbon atoms in the ring which comprises reacting the naphthalene hydrocarbon with a cycloparaffin having less than 5 carbon atoms in the ring in the presence of aluminum halide and hydrogen chloride at temperatures below +50° C.

3. A process for treating naphthalene hydrocarbons having at least six carbon atoms in the ring to produce propyl derivatives thereof which comprises reacting the naphthalene hydrocarbon with cyclopropane in the presence of aluminum chloride and hydrogen chloride at temperatures below +50° C.

4. A process for treating naphthalene hydrocarbons having at least six carbon atoms in the ring to produce butyl derivatives thereof which comprises reacting the naphthalene hydrocarbon with cyclobutane in the presence of aluminum chloride and hydrogen chloride in temperatures below +50° C.

ARISTID V. GROSSE.
